UNITED STATES PATENT OFFICE.

MOREE FAWK LOPEZ, OF LOS ANGELES, CALIFORNIA.

DESIGN FOR A DOLL.

60,911.

Specification for Design.

Patented Apr. 25, 1922.

Application filed October 15, 1921. Serial No. 508,023. Term of patent 7 years.

To all whom it may concern:

Be it known that I, MOREE FAWK LOPEZ, a citizen of the United States, residing at Los Angeles, in the county of Los Angeles and State of California, have invented a new, original, and ornamental Design for a Doll, of which the following is a specification, reference being had to the accompanying drawing, forming part thereof.

The figure is a front view of a doll, showing my new design.

I claim: The ornamental design for a doll, as shown.

MOREE FAWK LOPEZ.
